UNITED STATES PATENT OFFICE.

BARTHOLOMEW BOWLER, OF PROVIDENCE, RHODE ISLAND.

MANIFOLD-RECORDING DEVICE.

1,147,137.

Specification of Letters Patent. Patented July 20, 1915.

Application filed September 15, 1914. Serial No. 861,791.

To all whom it may concern:

Be it known that I, BARTHOLOMEW BOWLER, a subject of the King of Great Britain, residing at Providence, in the county of 5 Providence and State of Rhode Island, have invented certain new and useful Improvements in Manifold-Recording Devices, of which the following is a specification.

My invention relates to devices for recording and copying purposes, such as a manifold sales book adapted for the record and multiple copy of correspondence or sales.

The essential objects of my invention are 15 to automatically clamp and support the record sheets during the recording operation, and to automatically release the same when the recording has ceased; to utilize the retaining means for carbon papers as 20 the guiding or separating means for the multiple paper strips; to accommodate detached record slips; to guard the block of folded record papers and furnish a temporary clamp for the upper surface of the 25 same; and to attain these objects in a structure inexpensive to manufacture, convenient in form, and facile to operate.

To the above ends essentially my invention consists in such parts and combinations 30 of parts as fall within the scope of the appended claims.

In the accompanying drawings which form a part of this specification, Figure 1 is a plan elevation of a sales book embodying 35 my invention, showing parts broken away, Fig. 2, a side elevation of the same partially open, Figs. 3 and 4, opposite end views of the same closed, Fig. 5, a section on line x , x , of Fig. 1, Fig. 6, a bottom plan view of a portion of the recording frame, and Fig. 7, a section of the same on line y , y , of Fig. 6.

Like reference characters indicate like parts throughout the views.

45 In the embodiment of the present invention the assemblage of parts comprises a base A of sheet metal having in the present instance upturned continuous side flanges α , and upturned lips α' upon one of its ends, 50 the whole comprising a partial receptacle with an open top, open at one end, and partially open at its other end. Integral with the inner ends of the flanges α are vertical

ears or bearing portions α^2 in which are mounted pintles, rivets or pivot pins B. 55

A guard for the package of record paper is represented in a general way C. In detail it consists of an open frame of bent sheet metal comprising flat side arms c and connecting end pieces c' , the latter being 60 provided with an inturned flange c^2 . The narrower surfaces or edges of the arms and end piece are adapted to rest upon the base A, and their broader surfaces or sides are a sliding fit within the base flanges α and lips 65 α' respectively. The ends of the arms c are upturned as at c^3 and are journaled on the pivot members B.

A member indicated in a general way by D is provided comprising a base d , an upright d' thereon, and a horizontal resilient arm d^2 . The portion d is fixed by rivets d^3 or otherwise to the base A near the end of the latter. A second pivoted frame E is provided which is also cut and bent from a 75 single piece of sheet metal, and it comprises flat side walls or arms e , whose upper edges at their outer ends are joined by a flat plate or bar e' , and the upper edges of whose opposite ends are connected by a similar plate 80 or bar e^2 .

A record plate F is pivotally mounted on a cross bar G in the frame sides e beneath the bar e' . In the present instance the end of the plate F is rolled over to form a sleeve 85 f loose on the bar G to form the pivotal connection. The plate F occupies the area between the walls e and extends rearwardly to a point below the bar e^2 . It rests upon the spring arm d^2 . 90

Combined carbon clamping and paper guiding members, in the present instance two in number, are similar in construction. One of these comprises a flat bar H fixed in the arms e in horizontal alinement with the bar G and in the rear thereof. Embracing this bar is a clamping arm h , U-shaped in cross-section, pivotally connected at one end through its side walls to the bar by a pivot pin h' . Intermediate the members H 100 and h is clamped an end of a strip of carbon paper I. The second clamping member is located in a slightly different plane from the first, and comprises the bar J in the walls e adjacent and behind the bar H; and 105 embracing this is the U-shaped or longitu-

dinally folded clamping arm *j* pivoted to the bar at one end by the pin *j'*. These parts clamp the carbon strip *K* which overlaps the strip *I*. In Fig. 6 one of the clamp-
5 ing arms is shown in broken lines in open position to permit the insertion or removal of a carbon sheet.

In the present instance a flexible cover is applied to my device consisting of a leather 10 strip *L* glued or otherwise fixed to the base *A* and adapted to be folded over upon the top of the device when records are not being made.

For recording material there is employed 15 in this instance a rectangular shaped package *M* of record paper in triplicate sheets, *m*, *m'*, *m''* arranged in fan folds *m³*. The package rests on the base *A* and is prevented from excessive endwise movement by 20 the portion *c* of the guard frame at one end, and by the portion *d'* of the spring arm at the other end. The sheets *m*, *m'*, and *m''* pass from the package respectively over the clamping arms *j*, *h*, and the sleeve 25 *f*, and thence horizontally forward over the plate *F* and under the bar *e²*, the carbon strips resting upon the upper faces of the record strips *m'* and *m''*.

In operation, record papers *m*, *m'*, and *m''* 30 are together manually drawn forward the required distance by grasping their projecting forward ends. In order to insure that no excess of paper escape from the folds *m³* of the package during this operation, it is 35 found advantageous at times to manually press the free end of the frame *C* downwardly and maintain the bar *c²* in tight frictional contact with the upper face of the top fold. The pivotal character of this 40 frame accommodates it to a package of any height. The operator applies his pencil to that portion of the face of the strip *m* which is upon the plate *F*, with his hand resting upon the bar *e'*. The weight of the hand 45 serves to depress the frame *E*, and subject the plate *F* to the pressure of the spring arm *d²*, and by virtue of this action the record strips are held tightly clamped between the plates *F*, *e'*, and *e²* against accidental movement, and a firm backing afforded during the 50 recording operation. When the pressure of the hand is removed the spring arm returns the parts to normal position.

Successive lengths of records are detached 55 by upwardly bending the advanced portions of the record strips against the forward edge of the bar *e²* and then transversely and rearwardly pulling them thereagainst to tear them. The served triplicate, which the operator preserves, is placed on the base *A* beneath the package *M*, access being afforded by raising the package with the members *C* and *E* in some such positions as shown by 60 broken lines in Fig. 5. Derangement of the package *M* during this elevating operation 65

is prevented by the guard frame *C* which surrounds it. Meanwhile the slips already on the base *A* are prevented from escape by the walls *a* and lips *a'* which, with the base, 70 form a receptacle.

What I claim is:

1. A manifold recording device comprising a base, an open guard frame pivotally attached thereto to retain the package of paper strips, a second frame pivotally attached to the base and located above the first-named frame, carbon sheet clamping means upon the second frame, and means for automatically clamping and supporting the record sheets during the recording operation. 80

2. A manifold recording device comprising a base, an open guard frame pivotally attached thereto to retain the package of paper strips, a second frame pivotally attached to the base and located above the first-named frame, carbon sheet clamping means upon the second frame, a pivotally mounted paper-supporting member disposed between said frames, and a resilient support for 90 said pivoted member.

3. A manifold recording device comprising a base adapted to support a package of paper strips, an open frame pivotally connected with said base to surround said package, a second frame above the first-named frame and pivotally mounted on the base, means on the second frame for guiding strips of paper from said package, a pivotally mounted paper-supporting member disposed 100 between said frames, and carbon sheet holding means carried by the upper frame above said pivoted member.

4. A manifold recording device comprising a base adapted to support a package of paper strips, an open frame pivotally connected with said base to surround said package, a second frame above the first-named frame and pivotally mounted on the base, means on the second frame for guiding strips of paper from said package, a pivotally mounted paper-supporting member disposed between said frames, carbon sheet holding means carried by the upper frame above said pivoted member, and a resilient member fixed to the base and upon which the pivoted member rests during the recording operation. 110

5. In a device of the type set forth, the combination of a base, a guard frame resting upon the base and pivotally connected thereto at one end, a second open frame above the first frame pivotally connected at one end with the base, a resilient member upon the base within the first frame, a record plate pivotally attached to the second frame and supported by the resilient member, and an inturned flange upon the end of the first frame. 120

6. In a manifold recording device, the 125

combination of a base, a frame above the base pivotally connected with the base at one end, a record plate pivotally connected at one end to the frame, a resilient member 5 upon the base supporting the plate, cross bars in the frame in different horizontal planes, clamps upon the cross bars and a frame pivotally mounted on the base parallel therewith for holding a package of paper 10 strips.

7. In a device of the type set forth, the combination of a base, an open frame pivotally attached to the base and above the base, an upwardly extending member upon 15 the base, a plate pivotally attached to the frame resting upon said member and a second frame pivotally mounted on the base beneath the first-named frame for holding a package of paper strips beneath said upwardly extending member.

8. In a device of the type set forth, the combination of a base, an open guard frame pivotally attached at one end of the base and resting thereon, an inturned flange upon the 25 the end of the guard frame, a second frame above the first frame pivotally attached at

one end to the base and comprising lateral arms, a cross bar upon the forward end of said second frame, and a cross bar upon the rear end of said second frame, a plate yielding 30 mounted in the arms below the rear bar and a supporting member upon the base in contact with the plate.

9. In a device of the type set forth, the combination of a base, lateral upturned 35 flanges upon the base with upwardly directed lugs at one end thereof, a strip fixed to the base and extending beyond the same adapted to form a cover, a frame above the base, a member carried by the under side 40 of said frame, pivot members connecting the frame to support the paper with the lugs and an upwardly extending member supporting said member carried by the frame and fixed to the base.

In testimony whereof I have affixed my signature in presence of two witnesses.

BARTHOLOMEW BOWLER.
